UNITED STATES PATENT OFFICE.

ATAKA OHNO, OF HONGO-KU, TOKYO, JAPAN.

CENTRIFUGAL SEPARATOR.

Application filed November 10, 1920. Serial No. 423,204.

To all whom it may concern:

Be it known that I, ATAKA OHNO, a subject of the Emperor of Japan, and a resident of No. 3 Yayoi-Cho, Mukogaoka, 5 Hongo-Ku, Tokyo, Empire of Japan, have invented new and useful Improvements in Centrifugal Separators, of which the following is a specification.

This invention relates to improvements 10 in centrifugal separators and relates more particularly to means for automatically adjusting the rotation of the separator but without sustaining the loss of energy, and has for its object to provide a device of the 15 character wherein the material containing vessel is carried by a special equalizing medium of novel character, hereinafter called "balancer", instead of directly connecting it with the rotating shaft as in the 20 ordinary case.

A further object of the invention is to provide a device of the character which is simple in construction, durable, efficient in separating solid matters from liquid material or separating various other solid and liquid mixtures in accordance with the difference of the specific gravities between the 25 respective material.

In order that the invention may be 30 thoroughly understood and easily carried into practical effect, I have appended hereunto a sheet of explanatory drawing, in which:—

Fig. 1 is a side elevation, half sectioned, 35 showing the novel balancing member according to the invention.

Fig. 2 is a plan, along the line A—A of Fig. 1.

Fig. 3 is a sectional view taken on the 40 line B—B of Figure 1.

In the drawing the vertical shaft which receives rotary motion from a suitable source underneath in an ordinary manner is represented by the reference numeral 1. 45 2 is the balancer, preferably in the form of a fly-wheel having a specially enlarged and upwardly elongated hollow hub 3, which is adapted to be placed over the top end of the vertical shaft 1 in such a manner as to 50 leave sufficient space between the top end of the vertical shaft and the inner wall of the top or crown end of the hub 3, as shown.

Spaced from and adjustably mounted upon the upper end of the vertical shaft is an 55 intermediate ring 4. This ring is provided with four holes substantially at the points

diametrically opposite and at right angles to each other. These holes are adjustably engaged by threaded pins 5, 5^a, 5^b and 5^c, respectively.

Whilst the inner end of each of the two opposed pins 5 and 5^b reaches the hole 6 which is provided upon the upper end portion of the shaft 1, the other two opposed pins 5^a and 5^c are adapted to join the ring 4 with the hub 3 of the balancer.

The hub 3 is as shown reduced from the enlarged vertex to an upwardly projecting extension 10, which carries at its upper end a receiver ring 7, which, in turn, is adapted 70 to carry thereon a suitable vessel containing the material to be treated upon, not shown in the drawing. Any suitable means may be employed to hold the vessel on said receiver ring.

Spaced from the extension 10 and adjustably supported within the receiver ring 7 is an intermediate ring 8, which is provided with four holes substantially at the points diametrically opposite and at right angles to each other. These holes threadedly engage the pins 9, 9^a, 9^b and 9^c, respectively. Whilst the extension 10 is supported by two opposed pins 9 and 9^b, the other two opposed pins 9^a and 9^c, are adapted to support the receiver ring 7, as will be readily understood. In short, the invention contemplates the use of a pair of universal joints through the medium of which the vessel containing the material is connected with the balancer, which, in turn, is connected with the vertical shaft 1, likewise through the medium of an universal joint.

In practice, the container is placed in an appropriate manner upon the receiver ring 7 and rotated, motion being communicated thereto from the vertical shaft 1, but by reason of an unequalized condition of the load, the receiver ring 7 will be caused to list itself in one direction. Furthermore, 100 by reason of an unequal density of the contents within the container, and in view of the fact that the centrifugal force behaves in accordance with the fundamental formula of

$$F = \frac{v^2}{r}$$

the container will be caused to deviate itself toward the direction where the effect of the 110 centrifugal force is most intensified, the device providing means for so mounting a

container or centrifuge and a fly-wheel that they may be rotated in unison about their combined center of gravity.

Having thus fully described my invention, what I claim, and desire to secure by Letters Patent of the United States, is:—

1. A vertical revoluble shaft, a ring concentric therewith and pivotally mounted thereon, a fly wheel having an upstanding hollow hub in which the upper portion of the shaft and said ring are concentrically arranged, said hub being pivotally mounted on said ring, the pivotal axis of said ring being at right angles to that of said hub;
- 10 15 a second ring concentric with and pivotally mounted on the hub, and a container holding member concentric with said second ring and pivotally mounted thereon, the pivotal

axis of said second ring being at right angles to that of said container holding member.

2. A vertical revoluble shaft, a fly wheel having an upstanding hollow hub into which the upper end of said shaft extends, said hub being mounted on said shaft for universal angular movement, and a container holding member mounted on the upper portion of said hub for universal angular movement.

In testimony whereof I affix my signature in presence of two witnesses.

ATAKA OHNO.
